UNITED STATES PATENT OFFICE.

HARRY J. ILETT, OF LA GRANGE, ILLINOIS.

FASTENING DEVICE.

1,278,666.

Specification of Letters Patent. Patented Sept. 10, 1918.

Application filed July 21, 1917. Serial No. 181,947.

To all whom it may concern:

Be it known that I, HARRY J. ILETT, a citizen of the United States, residing at La Grange, in the county of Cook and State of Illinois, have invented certain new and useful Improvements in Fastening Devices, of which the following is a specification.

My invention relates to fastening devices and has especial references to devices of this 10 character for securely holding together the members of bed frame structures, such as the side rails and the head and foot panels.

One of the objects of my invention is to provide a fastening device especially adapted 15 for securing the side rails of bed frame structures, at their respective ends, to the head and foot panels thereof, which will not only support the members in place but which will tightly and firmly draw the members 20 together so that there can be no relative movement of the parts, and which is adjustable to compensate for any shrinkage of the wooden parts of the frame structure.

Another object of my invention is to provide 25 a fastening device for the members of bed frames which draws the members so firmly and closely together as to not leave any openings within which to harbor insects.

Another object of my invention is to provide 30 a fastening device that is cheap to construct, easy of application and simple in operation.

Other and further objects of my invention will become readily apparent to persons 35 skilled in the art, from a consideration of the following description when taken in conjunction with the drawings, wherein:—

Figure 1 is a side elevation of a bed rail and the post of an end panel showing some 40 of the parts in section and showing my fastening device attached thereto.

Fig. 2 is a section taken on line 2—2 of Fig. 1.

Fig. 3 is a section taken on line 3—3 of Fig. 1.

Fig. 4 is a section taken on line 4—4 of Fig. 1.

In all the views the same reference characters are employed to indicate similar parts. 50 5 is the end panel of the bed structure, such as the head board or foot board of a bed, and 6 is a side rail of such a structure. Near the end of the side rail is secured a block 7, as usual in such structures. The 55 end of the rail 6 and the block 7 are flush and make intimate contact with the con-

fronting surfaces of the post 5. On the post 5 is mounted, as at 8, a slotted plate 9, which overlies a mortise and is secured to the post, as by screws 10. The plate 9 is centrally perforated, with a "key hole" slot 11, having an enlarged intermediate portion 12 and relatively narrow portions 13 and 14, which are in the same vertical plane. The 60 slideable bolt 15 passes neatly through the perforated plate 16, which is secured to the outer surface of the block 7, as by screws 17. The outer end of the bolt 15 is slotted to receive a cam 18. The legs, of which there are two, one on each side of the slot of the 65 bolt 15, are turned into eyes 19 and 20, the cam 18 being pivoted to the bolt 15, by a pin 21 which passes through the eyes 19 and 20 and permits free pivotal movement of the cam. The cam has a rounded eccentric portion 22, and a flat retaining portion 23, the latter to bear against the plate 16 when the parts are in locked position. The front 70 end of the bolt 15 is reduced to provide a stem 23, which is threaded to receive an adjustable nut 24. A nut, or enlargement 24 is sufficiently small to pass through the enlarged portion 12 of the slot 11 but will not pass through the narrower portion 14 of the slot. Projecting from the ends of the side rails 75 6 are dowel pins 25, one preferably above the fastening device and the other below it. These dowel pins are, preferably, fixed in the side rail and project sufficiently into the post 5.

To assemble the parts, the cam 18 is rotated outwardly upon its pivot 21, to a position substantially as shown in dotted lines in Fig. 2, after which the bolt 15 is pushed forwardly to project as far beyond the end 95 of the side rail 6 as may be. Then the side rail is placed so that the nut 24 will enter the enlarged portion 12 of the slot 11. This may be done before the dowel pins 25 in the side rails will enter the respective openings 100 in the post 5. Then the side rails and the post may be pushed together whereby the bolt 15 will be moved axially into approximately the position shown in Fig. 2. Thereupon the cam 18 should be forcibly moved 105 into the position shown in full lines in Fig. 2, whereupon the nut 24 is drawn, by action of the cam, firmly against the plate 9. The cam when moved upon its pivot, first engages the abutment 16 by its curved surface 22, 110 and further movement of the cam, as driving it in by a hammer or the like, will move

the bifurcated end of the bolt 15 tending to draw it out of the block 7, thereby causing the nut 24, in its engagement with the plate 9, to draw the side rail 6 and the block 7 firmly into contact with the post 5. When the flat surface 23 of the cam is moved into contact with the confronting surface of the plate 16 the cam will thus be caused to remain in its final position until forced out of it by some especially applied means for the purpose. A hole 26 may be drilled into the surface of, or through the cam, within which to insert an instrument to turn it upon its pivot and move it from the position shown in full lines in Fig. 2 to the position shown in dotted lines, prior to disassembling the parts. Or an instrument may be pushed between the cam and the confronting inner surface of the bed rail to push the cam out of its locked position. The nut 24 may be adjusted on the threaded stem 23 of the bolt 15 to compensate for any shrinkage of the contacting wooden parts of the structure.

25 The device is very easily and quickly assembled. After the plates 9 and 16 have been properly placed in their respective positions and secured thereto by the respective screws, the bolt or bar 15 is passed through 30 the plate 16 and the block 7, after which the

nut 24 is screwed on the threaded stem 23 of the bolt 15. The parts are then ready for fastening the bed structure members together, which is accomplished in the manner heretofore described.

35

Having described my invention, what I claim is:

A fastening for bed frame members comprising a bolt slidably supported on the side rails of the frame; a nut, adjustable on the outer end of the bolt to compensate for shrinking of the parts; a slotted plate secured to the end panel of the frame to receive the bolt and having a part beyond which the nut will not pass; a cam pivoted to the inner end of the bolt and having a flat face to hold it in place and an abutment for the free end of the cam supported on the rail, whereby to draw and hold the parts of the structure together when the cam is forcibly moved with its flat face into contact with the said abutment.

In testimony whereof I hereunto set my hand in the presence of two subscribing witnesses.

HARRY J. ILETT.

In the presence of—

FORÉE BAIN,
LORETTA A. GIBBONS.
